UNITED STATES PATENT OFFICE.

KERKOR TOROSIAN, OF MANCHESTER, NEW HAMPSHIRE.

WALL CONSTRUCTION.

1,349,793.

Specification of Letters Patent. Patented Aug. 17, 1920.

Application filed June 12, 1919. Serial No. 303,566.

To all whom it may concern:

Be it known that I, KERKOR TOROSIAN, a citizen of the United States, residing at Manchester, in the county of Hillsborough 5 and State of New Hampshire, have invented certain new and useful Improvements in Wall Constructions; and I do declare the following to be a full, clear, and exact description of the invention, such as will enable others skilled in the art to which it appertains to make and use the same.

This invention relates to wall constructions, and more specifically to an improved brick wall construction.

One object of this invention is to provide an improved wall construction which facilitates the operation of building brick walls, so as to effect a great saving in the time required for building a wall of predetermined 20 dimensions, thereby effecting a great saving in the cost of such wall.

A further object is to provide an improved brick wall construction of this character which effects a very considerable saving 25 in mortar.

A further object is to provide an improved wall construction of this character in which each course of bricks is a tie-course, and in which the exposed surface 30 of each outer brick between the corners of the wall is equivalent in shape and area to that of each similarly located brick.

A further object is to provide an improved wall structure of this character which 35 is exceedingly strong, rigid and durable, and which withstands and resists the vibrations which are caused by the travel of heavy vehicles over cobbled streets or other uneven surfaces, and which will withstand the strain 40 consequent to high winds, earthquakes, etc.

Other objects and advantages may become apparent to persons who read the following details of description in connection with the accompanying drawings, in which:

Figure 1 is a perspective view illustrating 45 portions of two meeting walls of different thicknesses.

Fig. 2 is a sectional view, the section being taken substantially along the line 2—2 of 50 Fig. 1.

Fig. 3 is a perspective view somewhat similar to Fig. 1, but the thicker one of the two walls in Fig. 3 being less thick than the thicker wall shown in Fig. 1.

Fig. 4 is a sectional view, the section

being taken substantially along line 4—4 of Fig. 3.

Fig. 5 is a perspective view somewhat similar to Figs. 1 and 3, but showing a partition wall built entirely of square bricks, 60 this partition being narrower than the main wall.

Fig. 6 is a sectional view, the section being taken substantially along the line 6—6 of Fig. 5. 65

Fig. 7 is a perspective view of two of the bricks used.

Referring to these drawings in detail, in which similar reference characters correspond with similar parts throughout the 70 several views,—

A main or outer wall 7 and branch walls 8, 9 and 10 are shown in Figs. 1, 3 and 5 respectively, and it will be seen that the bricks of the branch wall are interlapped 75 with those of the main wall in each instance. It will also be seen that the walls 7, 8 and 9 are composed of square bricks 11 and half-square bricks 12, that is, bricks 11 whose horizontal surfaces are square, and bricks 80 12 each of whose horizontal surfaces are equal in area and shape to the horizontal surfaces of one-half of one of the square bricks if divided in a plane passing vertically through the center and parallel with 85 two opposite edges of one of the horizontal surfaces. In other words, if each brick 12 is 2 x 4 x 8 (or the size of an ordinary brick), the square brick will be 2 x 8 x 8. Therefore, in referring to these two sizes 90 and shapes of bricks hereinafter, the terms square and half-square will be used. In constructing a wall of these bricks, the number and arrangement of the square and half-square bricks, in the courses, is proportional 95 to the thickness of the wall desired. For instance, in the wall 7, each course consists of one square brick and one half-square brick; in the wall 9, it will be seen that one course consists of one square brick and two 100 half-square bricks, and the adjacent courses (above and below) each consists of two square bricks; and in the wall 8, each course consists of two square bricks and one half-square brick.

By a careful observation of the walls, 7, 8 and 9, it will be seen that each course (consisting of all the bricks in the same horizontal plane) is a tie-course. In this connection, an important distinction is pointed out 105 110

between this wall construction and that of ordinary brick walls, it being well known that where the ordinary 2 x 4 x 8 bricks are used, each course is not a tie-course, that is, the longitudinal joints of each course are not bridged by the bricks of the course superposed thereon except at intervals of every five to ten courses, and the tie-course consists of 2 x 4 x 8 bricks which are turned 10 with their 2 x 4 ends outward, so that these bricks expose a 2 x 4 area, whereas each of the bricks between the tie-courses exposes a 2 x 8 area. By employing square bricks in connection with the half-square bricks, each 15 and every course may be a tie-course, as is clearly shown in the walls 7, 8 and 9. This not only provides a wall of great strength, rigidity and durability, but avoids the unsightly appearance presented by the tie-courses, thereby combining ornamentality 20 with excessive utility.

By combining the square and half-square bricks in the manner described and illustrated, the branch walls are interlocked with 25 the main wall 7, this interlocking being consequent to the interlapped relation of the square bricks at the junction of the two walls.

By employing the square and half-square bricks in combination, as described, the necessity for dividing bricks is entirely eliminated in an ordinary wall structure, and it will be seen that partition walls of 30 eight inches or multiples of four inches may 35 be much more quickly and easily built with

bricks of this character than with the ordinary half-square bricks alone.

Although I have mentioned bricks 2 x 4 x 8 and 2 x 8 x 8 for the sake of convenience in describing the invention, it is not intended 40 to limit the invention to these exact dimensions, but changes may be made within the scope of the inventive ideas implied and claimed herein.

What I claim as my invention is:—

1. A brick wall in which every course forms a tie course, each course being formed of relatively small oblong bricks and relatively large square bricks, the oblong bricks extending longitudinally of the wall and 50 the oblong bricks of one course being positioned between the square bricks of courses above and below the said course.

2. A brick wall in which every course is a tie-course and in which each outer brick between the corners of the wall exposes a surface equivalent in shape and area to that exposed by the similarly located bricks, substantially as specified.

3. A brick wall in which every course is a tie-course and in which each outer brick between the corners of the wall exposes a surface equivalent in shape and area to that exposed by the similarly located bricks, and a partition wall formed of bricks which are 60 interlapped with the bricks of said wall, substantially as specified.

In testimony whereof I have hereunto set my hand.

KERKOR TOROSIAN.
